(No Model.)

W. C. SWITZER.
FIFTH WHEEL.

No. 355,799.

Patented Jan. 11, 1887.

UNITED STATES PATENT OFFICE.

WILLIAM C. SWITZER, OF COMANCHE, TEXAS.

FIFTH-WHEEL.

SPECIFICATION forming part of Letters Patent No. 355,799, dated January 11, 1887.

Application filed May 28, 1886. Serial No. 203,552. (No model.)

To all whom it may concern:

Be it known that I, WILLIAM C. SWITZER, a citizen of the United States, residing at Comanche, in the county of Comanche and State 5 of Texas, have invented a new and useful Improvement in Fifth-Wheels, of which the following is a specification.

My invention relates to improvements in fifth-wheels; and it consists of the peculiar 10 construction and arrangement of the various parts for service, substantially as hereinafter fully set forth, and particularly pointed out in the claims.

The object of my invention is to provide an 15 improved fifth-wheel which shall be simple and strong in construction, easily and readily applied or adjusted upon a vehicle for use, and cheap and inexpensive of manufacture.

A further object of my invention is to provide 20 a device of the class named, the parts of which shall be capable of movement upon each other with a minimum of friction and wear, and which shall be securely retained or connected together, so that they cannot be easily 25 displaced.

In the accompanying drawings, Figure 1 is a perspective view of my improved fifth-wheel. Fig. 2 is a vertical sectional view of my invention on the line $\alpha\alpha$ of Fig. 1. Figs. 3 and 4 30 are detached perspective views of the upper and lower sections of my improved fifth-wheel. Fig. 5 is a like view of the plate H.

Referring to the drawings, in which like letters of reference denote corresponding parts 35 in all the figures, A designates an axle of a vehicle to which my improved fifth-wheel is applied, and B designates a bolster which is carried by the upper section of the fifth-wheel, the axle and bolster being of any class or construction, as I do not desire to confine myself 40 to any kind of axle or bolster; but I would have it understood that I hold myself at liberty to apply the invention to any character of vehicle.

C designates the upper, and D, the lower, 45 section of my improved fifth-wheel, which are each made circular in form and fitted together so that they can rotate freely and easily upon one another when the vehicle turns out of a 50 straight line, as in rounding curves or corners.

The lower section, D, of my improved fifth-

wheel is curved at its upper edge in cross-section, as at d, and this curved edge constitutes the bearing-surface for the upper section, C, of the wheel, and the section C of the fifth-wheel 55 is made hollow in form, similar to a shell, and it is curved in cross-section to correspond to the curvature of the bearing-edge d of the lower section, D. These curved edges or faces of the upper and lower sections of the fifth-wheel 60 are fitted directly together, so that they bear upon each other, and the lower edges of the shell-like upper section, C, fit over and partially inclose the lower section, D, so that any lateral play or movement of the sections upon 65 each other is prevented, while they are free to rotate or turn upon each other to permit of the necessary movement of the front axle, A, in turning curves.

When the sections are rotated or turned, 70 they slide freely and steadily upon each other, and thus reduce the friction and wear on their respective bearing-surfaces, and, as the edges of the hollow section C fit over the edges of the section D they cannot become detached 75 or moved laterally and thus displaced.

The lower section, D, of the wheel is provided with integral straps or clips, E, which depend therefrom and have threaded ends, as is usual, and these clips straddle the axle A and receive 80 a clip-plate, e, and the securing-nuts e', whereby the lower section is securely and rigidly connected to the axle, while it can be readily disconnected therefrom by detaching the nuts and removing the clip-plate, as will be readily understood.

The upper section, C, of the fifth-wheel is provided with integral spaced lugs F, between which the ends of the bolster are fitted and retained in place thereby against lateral movement, and to prevent longitudinal play of the bolster I provide bolts f and nuts f', the former of which are suitably secured to or formed integral with the section C, and extend upwardly therefrom between the lugs F. 95

G designates the front end of the reach of any preferred kind, which extends across and bears on the upper section, C, of the fifth-wheel, and the upper edges of the reach are notched or recessed, as at g, to receive the lower edges 100 of the bolster, which is arranged across or at right angles to the reach, as clearly shown.

The front end of the reach is retained in place on and carried by the upper section of the fifth-wheel by means of a plate, H, which is bolted to the under side of the reach and extends longitudinally thereof, the ends of the plate being provided with the loop-shaped sockets h, which fit under and embrace the lower section of the fifth-wheel, whereby the upper section, C, and the reach are more firmly and securely connected to the lower section, D, while at the same time the upper and lower sections are free to rotate or turn upon one another.

The operation of my invention will be readily understood from the foregoing description, taken in connection with the drawings.

It will be observed that by the peculiar construction and arrangement of the parts of the fifth-wheel I am enabled to dispense with a king-bolt, and thus preserve the inherent strength of the axle; but I would have it understood that I hold myself at liberty to use a king-bolt if it is deemed desirable or necessary, and in lieu of making the sections C and D complete circles they may be made semicircular in form only.

I attach especial importance to the peculiar form of the sections C and D of the fifth-wheel, whereby I am enabled to decrease the friction and wear on the bearing-surfaces thereof and to prevent any lateral play or movement, and to cause them to rotate or turn steadily and freely on each other, as I am aware that fifth-wheels have been provided heretofore with projecting ribs on one section which fit in grooves on the other section.

Having thus fully described my invention, what I claim as new, and desire to secure by Letters Patent, is—

1. In a fifth-wheel, the combination of the lower section carried by the axle, an upper section bearing on the lower section and having the spaced lugs, a bolster fitted between the said lugs, a reach having its front end resting on the upper section, and the plate H, secured to the front end of the reach and having the loops h at its ends, which fit around the upper and lower sections, substantially as described.

2. In a fifth-wheel, the combination of the lower section, D, having the straps E, adapted to be secured to an axle, as A, and the transversely-curved bearing-edge d, the upper section, C, of hollow and curved form in cross-section, to snugly fit or embrace the bearing-edge d of the section D, and provided with the integral spaced lugs F, between which the ends of a bolster are retained in place, the bolts f, passing through the bolster, the reach carried by the upper section, C, and the plate H, secured directly to the reach, and having the loop-shaped sockets h, embracing the sections of the fifth-wheel, substantially as described, for the purpose set forth.

In testimony that I claim the foregoing as my own I have hereto affixed my signature in presence of two witnesses.

WILLIAM C. SWITZER.
